FLUID TREATING MECHANISM AND
METHOD

William Spencer Bowen, Westfield, N. J.

Application November 12, 1934, Serial No. 752,625

7 Claims. (Cl. 261—118)

The present invention relates to devices for treating fluids and embodies, more specifically, an improved fluid treating mechanism through which fluid may be directed to treat the same effectively in a desired fashion. More particularly, the invention relates to fluid treating mechanisms of the type wherein one fluid is directed into intimate relationship with another fluid or fluid bearing solid particles in suspension, a predetermined treatment being effected by the manner in which the fluids are brought into intimate association. The structure provided by the present invention is adapted for use in cooling or washing substances, as well as carbonating and treating in other fashions.

An object of the invention, accordingly, is to provide a fluid treating mechanism by means of which fluids may be subjected to desired physical and/or chemical reactions.

A further object of the invention is to provide a fluid treating mechanism of the above character wherein a substance to be treated is directed into the mechanism and subjected to certain operations by means of a treating substance which is also introduced thereinto.

The above objects are attained by providing a device wherein the treated substance is introduced into the device in the form of a solid circular spray which engages certain walls within the mechanism, the treating fluid being introduced into the device in such fashion as to have intimate contact with the substance to be treated where it strikes the walls within the device, the spray of fluid thus serving as a barrier to the free flow of the treating fluid therethrough.

Further objects, not specifically enumerated above, will be apparent as the invention is described in greater detail in connection with the accompanying drawing, wherein:

40 Figure 1 is a view in section taken in a vertical plane passing through the axis of a device constructed in accordance with the present invention, the plane of the section being indicated at I—I in Figure 2.

45 Figure 2 is a plan view of the device of Figure 1.

Figure 3 is an enlarged sectional view of the spray head shown in Figure 1.

With reference to the above drawing, a housing or treating member is shown at 10 and is provided with a bottom wall 11 which slopes downwardly and inwardly to an outlet 12. The top member 13 of the device is provided with a central opening 14 beneath which a downwardly extending cylindrical wall or tunnel 15 is pro-

vided. A treating fluid may be introduced into the tunnel 15 by means of an elbow or other fitting 16 which is preferably formed as a spiral to impart a whirl to the fluid about the axis of the tunnel 15. A spray head 17 is secured in the fitting 16 by means of a suitable flanged portion 18, the spray head 17 being provided with a cap or bonnet 19 within which a supply pipe 20 is secured.

A fan 21 is mounted upon the top member 13 and may receive fluid from any suitable source to direct the same through the whirl creating fitting 16. The fluid flows from the elbow 16 through the tunnel 15, the lower portion of which is formed with an outwardly diverging bell member 22 having a flaring extremity 23. The member 22 preferably extends downwardly into the housing 10 in such fashion that the fluid flowing therefrom must reverse its course and flow upwardly through a substantial portion of the housing 10 in order that it may escape through pipe 24.

Adjacent the top of the housing 10, a series of transverse baffle plates 25 are provided, these plates being mounted upon a ring or supporting member 26 and having a central sleeve 27 formed thereon to receive the tunnel member 15. The baffle members 25 thus are presented to all of the fluid which flows upwardly through the housing 10 and causes liquid and solid particles carried thereby to be removed effectively. Make-up liquid may be introduced into housing 10 through a suitable fitting 28.

The spray head 17 is formed with an axial stem 29 which is threaded at 30 in the bonnet 19. A nut or other device 31 may be formed on the top of the stem in order that it may be turned effectively. The stem 29 is formed with a spiral thread 32 which is received within the spray head 17 and imparts a whirl to the substance directed therethrough in order that upon being discharged the substance may flow in such fashion as to facilitate treatment thereof. The spray head 17 is formed with an annular seat 33 with which a valve plate 34 is adapted to cooperate. The valve plate 34 is secured upon the stem 29 and is thus moved with respect to the seat 33 to vary the valve opening as desired. In this fashion, the fluid will not only be directed outwardly in a circular spray but the fluid will have a whirling motion about the axis of the valve stem 29.

In addition to the imparting of a whirling motion to the fluid to be treated, the treating medium introduced through the fitting 16 is sub-

jected to a whirling action which may be in a direction contrary to the direction of whirl of the substance to be treated. This action will cause the fluids to be directed outwardly by centrifugal force and the treating fluid will thus be forced through the treated fluid adjacent the walls of the tunnel 15, at which time a violent scrubbing and intermingling of the fluid results.

The impact of the solid circular whirling spray 10 from the nozzle upon the wall 15 produces a powerful atomizing effect at the point where the treating fluid, due to centrifugal force, is most dense. Thus, not only is the treating fluid forced to contact the fluid from the nozzle but 15 such contact involves the maximum surface area of the treated fluid and the maximum density of the treating fluid.

While the invention has been described with specific reference to the accompanying drawing, 20 it is not to be limited, save as defined in the appended claims.

I claim as my invention:

1. A fluid treating device comprising a housing having an outlet adjacent the bottom thereof, 25 means to introduce a substance to be treated adjacent the top thereof, a tunnel within the housing and adjacent to and about the introducing means, means to discharge fluids from adjacent the top of the housing, means to introduce a treating fluid into the tunnel, and means 30 to discharge the substance to be treated from the first introducing means in a whirling spray, the means to introduce the treating fluid being formed to impart a whirl thereto.

35 2. A fluid treating device comprising a housing having an outlet adjacent the bottom thereof, means to introduce a substance to be treated adjacent the top thereof, a tunnel within the housing and adjacent to and about the introducing means, means to discharge fluids from adjacent the top of the housing, means to introduce a treating fluid into the tunnel, and means 40 to discharge the substance to be treated from the first introducing means to form a solid whirling spray between the introducing means and the tunnel, the means to introduce the treating fluid being formed to impart a whirl thereto in a direction opposite to that of the whirling substance.

50 3. A fluid treating device comprising a housing having an outlet adjacent the bottom thereof, a cylindrical tunnel adjacent the central top portion thereof, means to introduce a substance to be treated into the tunnel to form a solid spray within the tunnel to produce a fluid barrier therein of the substance to be treated, means 55 to introduce a treating fluid into the tunnel, a fluid outlet adjacent the top of the housing, and a member on the tunnel extending continuously outwardly and downwardly to form an expansion zone for the substance and the treating fluid whereby draft losses within the device will be reduced.

4. The method of treating fluid comprising introducing a substance to be treated into a relatively restricted tunnel within a housing and adjacent the top thereof, the substance being introduced adjacent the axis of the tunnel and in the form of a solid spray within the tunnel to produce a fluid barrier therein of the substance to be treated, directing a treating fluid axially of the tunnel and through the fluid barrier therein, removing the treating fluid adjacent the bottom of the housing, reversing the direction of motion of the treated fluid within the housing, and removing the treated fluid adjacent the top of the housing. 5

5. The method of treating fluid comprising introducing a substance to be treated into a relatively restricted tunnel within a housing and adjacent the top thereof, the substance being introduced adjacent the axis of the tunnel and in the form of a solid spray within the tunnel to produce a fluid barrier therein of the substance to be treated, directing a treating fluid axially of the tunnel and through the fluid barrier therein, expanding the treated fluid from the tunnel, removing the treating fluid adjacent 25 the bottom of the housing, reversing the direction of motion of the treated fluid within the housing, and removing the treated fluid adjacent the top of the housing. 10

6. The method of treating fluid comprising introducing a substance to be treated into a relatively restricted tunnel within a housing and adjacent the top thereof, the substance being introduced adjacent the axis of the tunnel and in the form of a solid spray within the tunnel to 30 produce a fluid barrier therein of the substance to be treated, imparting a whirl to a treating fluid and directing the same axially of the tunnel and through the fluid barrier therein, removing the treating fluid adjacent the bottom of the 35 housing, reversing the direction of motion of the treated fluid within the housing, and removing the treated fluid adjacent the top of the housing. 40

7. The method of treating fluid comprising introducing substance to be treated into a relatively restricted tunnel within a housing and adjacent the top thereof, the substance being introduced adjacent the axis of the tunnel and in the form of a solid whirling spray within the 50 tunnel to produce a whirling fluid barrier therein of the substance to be treated, imparting a whirl to a treating fluid in a direction opposite to the whirl of the treated substance and directing the treating fluid axially of the tunnel and 55 through the fluid barrier therein, removing the treating fluid adjacent the bottom of the housing, reversing the direction of motion of the treated fluid within the housing, and removing the treated fluid adjacent the top of the housing. 60
